PRINTING MACHINE FOR SMALL ARTICLES

James R. Newell, Creston, Iowa

Application November 26, 1946, Serial No. 712,440

5 Claims. (Cl. 101—311)

1

This invention appertains to improvements in printing machines such as used for stationary, calling cards, Christmas and birthday cards, or in other words for printing only a few lines on paper or cardboard. This machine is greatly simplified and very easy to operate as compared with existing machines of this class. It is operated by a hand crank and one half turn thereof brings the jaws of the impression plate and the type close together against the card or sheet to be printed, while the next half turn of the crank, in the same direction, opens the jaws and applies printing ink and is thereupon ready for the next printing.

The one great advantage of this machine is that the printing takes place on the underside of a card as the type set in the chase moves upwardly against the card which is placed upside down on the gauge plate. As a consequence the type need not be "locked" in the chase as is usual, and they cannot fall out of the chase when the latter is carried upside down.

The objects and advantages of this machine will be understood from the subjoined description with the aid of the accompanying drawing.

Figure 1 is a perspective view more or less diagrammatic and with some parts removed of a press constructed in accordance with the present invention, showing the elements in relative positions ready to start printing;

Figure 2 is a top plan view of Figure 1; and

Figure 3 is a vertical longitudinal section of the machine taken substantially on the line 3—3 of Figure 2, showing the elements in position in the act of printing.

In the drawings like numerals refer to the same details in the different views.

Numeral 10 denotes the frame and casing for the machine, at the front end of which a set of drawers 11 are to be found for holding the type needed. Above the drawers a chase 12 is shown in which the type is set up. This chase is secured removably, by screws or the like on the forward ends of a pair of arms 13, which are fulcrumed on a cross shaft 14 at the rear end of the frame 10.

Similarly on the forward ends of another pair of arms 15 overlying arms 13, the impression plate 17 is secured, which arms 15 are fulcrumed on a second cross shaft 16 mounted in the rear of the frame 10 above and paralleling the shaft 14.

The frame of the press at the front thereof is formed to provide a gauge plate 18 which overlies the type chase and extends rearwardly at a slight

2

downward inclination. This gauge plate has formed therein the opening 35 over which is placed the card or sheet which is to receive the printing impression. The length of the pairs of arms 13 and 15 which respectively carry the type chase and the impression plate, is such that when they are relatively oscillated upon their shafts 14 and 16 the faces of the type in the chase will be presented from below through the opening 35 toward and against the underface of the impression plate 17 if no sheet or card is on the gauge plate over the opening 35. If such a card or sheet is in position then, of course, the type will press against the underside of the sheet and the impression plate will press down thereon so as to compress the sheet between the type and the plate.

Some distance in front of the two cross shafts 14 and 16 and about midway between them as to height, a crank shaft 19 is supported in bearings in the sides of the frame 10. This shaft 19 is the operating shaft having a crank handle 20 on the outer side of the machine and a crank formation 21 in the middle thereof.

At each side of the machine is mounted a pair of spaced parallel guide rails 22 which extend lengthwise of the machine and lie in horizontal planes passing between the two pairs of arms 13 and 15.

Extending transversely of the machine forwardly of the crank shaft 19 is a spindle 24 upon each end of which is mounted a roller 23. Each of these rollers engages between a pair of guide rails 22, by means of which the spindle is maintained in position for back and forth movement.

Supported in spaced parallel relation by the spindle 24 are the two elbow levers 25 each of which comprises a short arm 25a and the long arm 25b. As shown the free end of the short arm of each lever 25 is attached to the spindle 24 and the long arms extend forwardly and upwardly each upon the outer side of an arm 13. These levers 25 are adapted to swing or oscillate on the spindle 24 during the back and forth movement of the spindle in the operation of the press as will be hereinafter made apparent.

At the forward ends of the arms 25b a transverse shaft 26a is supported by and extends across between the arms and adjacent to each end this shaft carries a roller 26b. Mounted on the shaft between the rollers is the ink roller 26. As will be clearly apparent the rollers 26b are positioned to ride upon the top edges of the arms 13 when the levers 25 move backward and forward.

Supported between the arms 13 just behind the type chase 12, is an ink plate 27 over the top surface of which the ink roller 26 moves when the type chase and impression plate are brought together. When the impression plate and type chase are separated the ink roller 26 moves forwardly across the faces of the type in the chase to transfer to the type faces ink which it has picked up from the plate 27.

The spindle 24 forms an element of a knee joint for an articulated thrust unit T which is connected between the upper and lower pairs of arms 15 and 13 respectively and which unit comprises an upper bifurcated leg 28 and a lower leg 29. These legs have ends in overlapping relation and are pivotally coupled by the spindle 24 which passes through such overlapping ends as is shown in Figure 1 thereby forming the complete joint between the arms.

At the center of the spindle 24 is connected one end of a connecting rod 30, the other end of which is connected with the crank 21. The upper ends of the furcations of the bifurcated arm 28 have hinge connections with the upper arm 15 by means of the transverse rod 32 and the lower arm 29 is connected at the end remote from the spindle 24, with the lower arms 13 by means of the transverse rod 33, the ends of which are connected to the arms 13 as illustrated.

The operation of the machine, which may be effected by means of the hand crank 20 or by mechanical means applied to turn the shaft 19, as may be desired, is as follows:

When the shaft 19 is rotated, preferably in a clockwise direction when viewing the machine from the left hand side or the side upon which the crank is shown in Figure 2, the crank 21 will apply back and forth movement to the connecting rod 30 whereby to move the spindle 24 forward and backward, the rollers 23 moving between the track rails adjacent thereto. This action will alternately straighten out and bend or fold the articulated thrust unit to respectively separate the pairs of arms 13 and 15 and swing them together at their forward ends.

As it will be readily apparent upon reference to Figure 3 when the articulated thrust unit is bent or folded the spindle will be moved rearwardly to the extreme position and the type chase and impression plate will be brought together in the opening 35 of the gauge plate 18. As will be clearly understood, if a sheet or card is at such time laid upon the gauge plate over the opening the desired printing impression will be made upon the underface thereof.

When the crank 21 swings forwardly to impart similar forward movement to the rod 30 the spindle 24 will be moved forwardly and the thrust unit T will be straightened out to the position shown in broken lines in Figure 3 and the type chase and impression plate will be separated.

When the spindle 24 is moved rearwardly for a printing operation the levers 25 will be drawn rearwardly and the ink roller will be caused to move backwardly and across the ink plate 27 as shown in Figure 3.

As the arms 13 and 15 are swung apart at their forward ends the levers 25 will be moved forwardly and the ink carrying roller 26 will roll over the type to apply ink thereto. Thus with each complete rotation of the crank shaft 19 the full cycle of operation will be performed as will be readily apparent.

I claim:

1. A printing press of the character described,

comprising a frame, an upper and a lower pair of substantially horizontally disposed arms having forward and rearward ends, means pivotally supporting the rearward ends of the upper and lower pairs of arms in the frame for vertical swinging movement whereby the forward ends of the arms may be alternately brought together and separated, an impression plate carried by the forward ends of the upper arms, a type chase carried by the forward ends of the lower arms, means for supporting a sheet of material in the meeting plane between the impression plate and type in the chase, and means for synchronously swinging the said pairs of arms to alternately bring together and separate the impression plate and the type chase, the said means for synchronously swinging said pairs of arms comprising an articulated two-part thrust unit connected between the pairs of arms, a pivot for the articulation, means securing the pivot against movement in the direction of movement of the arms but permitting movement of the pivot lengthwise of the arms, and a reciprocating rod connected to the articulation between the parts of said unit for effecting upon reciprocation the alternate straightening and folding of the articulated unit.

2. A printing press of the character described comprising a frame, a gauge plate for supporting a sheet of material upon which printing is to be applied, the gauge plate having an opening over which said sheet of material is positioned, an upper and a lower pair of arms having forward and rearward ends, means pivotally supporting the rearward ends of the upper and lower pairs of arms in the frame for vertical swinging movement whereby the forward ends may be alternately brought together and separated, an impression plate carried by the forward ends of the upper arms, a type chase carried by the forward ends of the lower arms, said gauge plate being positioned between the impression plate and the type chase and the impression plate and type chase being disposed to meet within the opening of the gauge plate when brought together, an extensible and foldable coupling unit connected between the upper and lower pairs of arms, and power means connected with said unit for effecting the extension and folding of the same, said unit when extended functioning to separate the forward ends of the pairs of arms and when folded functioning to bring the forward ends of the arms and the impression plate and type chase carried thereby together in said gauge plate opening, with an ink plate carried by the lower arms adjacent to the type chase, an ink roller adapted to move back and forth between the ink plate and the type chase, and an operative coupling between the ink roller and said extensible unit for effecting the retraction of the roller from the chase onto the ink plate upon the folding of the extensible unit and the movement of the ink roller forwardly over the type chase upon the extension of said unit.

3. A printing press of the character described comprising a frame, a gauge plate carried thereby and having an opening therein, the gauge plate being designed to have placed thereon over the opening a sheet of material upon which printing is to be applied, an upper and a lower pair of arms having forward and rearward ends, means pivotally supporting the rear ends of the upper and lower pairs of arms in the frame for vertical swinging movement whereby the forward ends may be alternately brought together and separated, the forward ends of the lower pair of

arms being disposed beneath the gauge plate and the forward ends of the upper pair of arms being disposed above the gauge plate, an impression plate carried by the forward ends of the upper pair of arms, a type chase carried by the forward ends of the lower pair of arms, the impression plate and type chase being positioned to be brought together in said gauge plate opening by the bringing together of the forward ends of the pairs of arms, a pair of vertically spaced substantially horizontally positioned tracks disposed at each side of the pairs of arms substantially midway of the lengths of the arms, a spindle extending transversely between the upper and lower pairs of arms, a roller upon each end of the spindle, each roller being rotatably supported between a pair of tracks, an extensible and foldable thrust unit comprising an upper arm and a lower arm, the arms of said unit being coupled together by said spindle and the upper end of the upper arm being pivotally coupled with the upper pair of arms and the lower end of the lower unit arm being pivotally coupled with the lower pair of arms, and means for applying forward and rearward thrust to said spindle to effect the extension and folding respectively of said thrust unit.

4. A printing press of the character stated in claim 3, with an ink plate carried by the lower arms, a roller adapted to move on the lower arms between the ink plate and the type chase, and means for retracting the roller onto the ink plate and upon the movement of the impression plate and

type chase together and for shifting the roller forward over the type chase upon the movement of the type chase and impression plate apart.

5. A printing press of the character stated in claim 3, with an ink plate carried by the lower pair of arms immediately rearwardly of the type chase, an inking roller, a pair of crank arms each pivotally connected at one end to said spindle and extending forwardly on one side of the type chase, a shaft connecting the forward ends of the crank arms, said roller being rotatably supported upon the crank arm carried shaft, and roller means upon the last mentioned shaft resting upon the top edges of the arms of the lower pair.
